UNITED STATES PATENT OFFICE.

WILLIAM ALLEN MINIFIE, OF LITTLE FALLS, NEW JERSEY, ASSIGNOR TO WILLIAM H. BEATTIE, OF LITTLE FALLS, NEW JERSEY.

WOVEN PILE FABRIC.

No. 923,682.

Specification of Letters Patent.

Patented June 1, 1909.

Application filed February 6, 1909. Serial No. 476,364.

To all whom it may concern:

Be it known that I, WILLIAM A. MINIFIE, a citizen of the United States, and a resident of Little Falls, in the county of Passaic and State of New Jersey, have invented a new and Improved Woven Pile Fabric, of which the following is a full, clear, and exact description.

The invention relates to tapestry, Brussels or velvet carpets or rugs, and its object is to provide a woven pile fabric in which the pile tufts are securely held in place and an exceedingly strong and durable body weave is provided to insure long life of the fabric when in use. In order to attain this result use is made of a stuffer chain, upper and lower filling shots, pile tufts held on the upper filling shots and pairs of binding threads for the said filling shots, the binding threads in each pair passing simultaneously around one set of filling shots and singly around the other filling shots.

A practical embodiment of the invention is represented in the accompanying drawings forming a part of this specification, in which similar characters of reference indicate corresponding parts in all the views.

Figure 1 is an enlarged longitudinal section of the fabric; Fig. 2 is a transverse section of the same on the line 2—2 of Fig. 1; Fig. 3 is an enlarged longitudinal section of a modified form of the improved fabric; and Fig. 4 is a cross section of the same on the line 4—4 of Fig. 3.

Over the stuffer chain A pass the upper filling shots B, on which are looped the pile tufts C, clamped in place on the stuffer chain A by the upper filling shots B, as plainly indicated in the drawings. Lower filling shots D extend under the stuffer chain A and are arranged alternately relative to the upper filling shots B, as plainly indicated in Fig. 1, and the said upper and lower filling shots B and D are engaged by pairs of binding

threads E and E', which pass simultaneously over each upper filling shot B and singly and alternately under the lower filling shots D, but this arrangement may be reversed, as shown in Figs. 3 and 4, in which the binding threads E² and E³ pass simultaneously around the lower filling shots D', and singly and alternately around the upper filling shots B', extending across the top of the stuffer chain A' and carrying the pile tufts C'.

By the arrangement described an exceedingly strong and durable fabric body is provided, and the pile tufts C' are securely held in place by the upper filling shots B' clamping the loops of the pile tufts C' onto the stuffer chain A'.

Having thus described my invention, I claim as new and desire to secure by Letters Patent:

1. A woven pile fabric, comprising a stuffer chain, upper filling shots extending over the said stuffer chain, lower filling shots extending under the said stuffer chain, pile tufts on the upper filling shots, and a pair of binding threads passing around each one of the filling shots of one set of the said filling shots, and passing singly and alternately around the other set of filling shots.

2. A woven pile fabric, comprising a stuffer chain, upper filling shots extending over the said stuffer chain, lower filling shots passing under the stuffer chain, pile tufts looped on the upper filling shots, and binding threads passing around each of the said upper filling shots and singly and alternately around the lower filling shots.

In testimony whereof I have signed my name to this specification in the presence of two subscribing witnesses.

WILLIAM ALLEN MINIFIE.
